UNITED STATES PATENT OFFICE

2,511,497

PORTABLE ODOR ADSORPTION DEVICE

George S. Dauphinee, Brooklyn, N. Y., assignor, by mesne assignments, to W. B. Connor Engineering Corporation, New York, N. Y., a corporation of New York

Application August 16, 1946, Serial No. 691,143

4 Claims. (Cl. 183—35)

1

This invention relates to an odor adsorption or odor removing device and the like and more particularly to a portable or adjustable unit for adsorbing and removing offensive odors from a confined space.

A problem frequently involved in ventilation is an isolated source of offensive odor which then permeates the entire space. For example, in the evacuation of battle casualties by hospital ships or by airplanes, the sick bays and cabins because of draining wounds, old odorous casts, gangrenous wound odors and other infections become the source of odors which are not only offensive to the patients, but frequently have caused the crew of the evacuation craft to become ill.

Another source of offensive odor is confined storage spaces for meat and other food products and which odors might putrify or otherwise affect the stored produce or the source might be only one or a very few of the products which might contaminate the other.

Heretofore these problems have usually been met by the installation of ventilating equipment which required the incorporation of undesirably large air movements. For instance portable fans or other devices for increasing the volume of ventilating air through the cabin or other confined space have been used. However, ventilation with replacement of malodorous air by clean outside air cannot be utilized as a means of overcoming odors in such confined spaces as a hospital plane or the sick bay of a hospital ship, or a storage compartment. In the pressure type cabins it would be impossible. Furthermore, the extent of ventilation required to constantly remove vitiated air would cause drafts and, at altitudes, cold, and under conditions of continuous evolution of offensive odors, rapid air movement at the rate of a complete change per minute is not even sufficient to control the odor.

Chemical sprays and vapors have also been used but these are objectionable because of their own odor. Most of these deodorants utilize formaldehyde as the active agent and constant inhalation of these fumes often causes throat irritation and may cause inflammations such as coryza and bronchitis. Other deodorants, such as perfumes and ozone are also unsatisfactory, the first because it simply masks the offensive odor and the latter because it may be harmful to the human body when it is concentrated sufficiently to exhibit deodorant action.

The method with which the present invention is concerned on the other hand involves the

2

removal of odors by adsorption in activated carbon or other adsorbent media such as alumina or silica gel, with subsequent recirculation of the air. Although this principle of air purification is of course well-known, designers have been confronted with serious obstacles in its practical and commercial application to air conditioning service in small confined spaces, particularly evacuation air craft, sick bays, etc.

10 In the past the principle of adsorption was utilized in connection with surgery by the application of carbon-impregnated dressings to the wounds.

15 A particular problem has been confronted in removing by adsorption the sub-blanket odor from the patient's bed. In order to meet this problem, the airflow needed to produce a slight negative pressure under the blanket on a cot without causing a draft perceptible to the patient first had to be established. If the airflow is too strong, it will cause discomfort and pain to the patient and if too weak, it will fail in its purpose.

20 It is, therefore, among the objects of the present invention to provide an adsorption device of the character indicated which is light-weight and portable, which can easily be adjusted for the removal of odors from any confined space, and which will not impose any additional burden upon their limited ventilation facilities.

25 30 Another object is the provision of an adsorption device which will effect complete removal of the offensive odor without causing objectionable drafts.

35 A still further object is to provide an adsorption device which can easily be assembled and disassembled.

40 A cognate and more specific object is to provide an adsorption device for removing the sub-blanket odor from litters and sick beds.

45 45 Further objects and advantages inherent in the invention will become apparent from the following specification taken in conjunction with the accompanying drawing showing a preferred embodiment and in which

Figure 1 is a perspective view with portions broken away showing an adsorption device according to the invention.

50 Figure 2 is a section taken along the line 2—2 of Figure 1.

Figure 3 is a section taken along the line 3—3 of Figure 1.

Figure 4 is a section taken along the line 4—4 of Figure 1, and

55 Figure 5 is a sectional view of the fan unit

casing drawn to an enlarged scale showing how the device may be fastened in position.

Referring in greater detail to the drawing, throughout which the same reference characters indicate the same or analogous parts, the device according to the invention comprises a canister generally indicated at 10 which consists of a casing 11, preferably of cylindrical shape, containing a bed of granular activated carbon 12. The casing 11 is provided with perforations 13 to admit access of the surrounding air.

The casing 11 is closed at one end 14 but is provided with an opening 15 at the other end, which is provided with a nipple or collar 16. A coupling 17 of hard rubber or similar material frictionally and detachably engages the nipple 16. The other end of the coupling 17 is cemented or otherwise attached to the fan unit casing 18 which at its other end is attached to the collar 19 of the flexible exhaust tubing 20.

The motor 21 which is mounted within the casing 18 by means of the clamp 22 drives the axial flow exhaust fan 23.

The other end of the tubing 20 is provided with a collar 24 to which the tube 25 is connected. A pin 25a mounted transversely in the tube 25 serves as a bearing for the butterfly valve which is held frictionally on the pin.

The motor 21 may be connected to a power outlet by means of the cord 27 running through the tubing 20, the cord anchor 28 to the motor and connected to the plug 29.

For the purpose of keeping the blankets and bed clothes spaced from the canister so as to admit access of the foul air thereto, the casing 11 may be provided with guard wires 30 which are connected to a pair of rings 31 which can easily be slipped on to the casing.

The device may be fastened to the bed or litter by means of a strap 32 which is buckled about the fan unit casing 18 by means of the buckle 33. This strap is also connected to a clip 34 by means of the swivel 35. The clip may then be attached to the blanket 36.

In operation, when applied to a sick bed or litter, the canister is placed at the patient's feet or at some other convenient place and fastened in position as shown in Figure 5 of the drawing with the exhaust tubing hanging over the edge of the bed or litter.

The odor permeated, sub-blanket air is drawn by the fan 22 through the carbon bed 12 which collects the offensive vapors and gases, and the purified air is then exhausted through the tubing 20 to the room for subsequent re-circulation. It will thus be seen that the room air is in no manner vitiated.

It has been found that an optimum air flow through the carbon canister of 10 cubic feet per minute will maintain a negative pressure sufficient to cause the withdrawal of the foul air without causing perceptible drafts. However, velocity of the air flow may be regulated by means of the butterfly 26. Thus if it should be desired to decrease the air flow, the butterfly valve 26 is turned to a transverse position whereas its longitudinal position will permit an increased flow.

The carbon bed should preferably have a thickness of $\frac{3}{4}$ inch within the circumference of the canister which for the specific purpose described may be 3 inches in diameter with an overall length of 8 inches and a weight of about 20 ounces. The carbon once saturated can of course be reactivated and reused or simply be replaced.

The motor may be very small, about 27 volts,

weighing about 7 ounces and developing approximately 11,000 R. P. M. with a ten watt energy consumption.

The exhaust tubing may have an approximate length of 18 inches and a weight of about 5 ounces.

The device thus described will only be slightly heavier than two pounds and have very small bulk which will make it easy to transfer and adjust to various situations where odor removal is required.

It should be understood, however, that the application of the device is not limited to hospital or litter use, but may be applied to any confined space.

Furthermore, it should be understood that this disclosure is given by way of example and not by way of limitation. On the other hand, the invention lends itself to a variety of expressions within the appended claims.

What is claimed is:

1. A portable and detachable odor adsorption device for removing offensive odors underneath the coverlet of a sick bed, litter or the like, said device comprising a canister disposable under said coverlet and having an outer casing and an inner casing defining a central air passageway, said casings having perforate side walls spaced from one another and closed at both ends, odor adsorption material filling the space between said walls, said air passageway being closed at one end and open at the opposite end, a flexible tubular member connected to the open end of said passageway, and means in said tubular member for drawing purified air through said air passageway and discharging it through said tubular member to a point outside said coverlet, whereby to produce a relatively low pressure area under the coverlet maintaining a flow of air inwardly through the coverlet and preventing the escape of malodorous air outwardly of the coverlet.

2. A portable and detachable odor adsorption device for removing offensive odors underneath the coverlet of a sick bed, litter or the like, said device comprising a canister disposable under said coverlet and having an outer casing and an inner casing defining a central air passageway, said casings having perforate side walls spaced from one another and closed at both ends, odor adsorption material filling the space between said walls, said air passageway being closed at one end and open at the opposite end, a nipple for said open end, a coupling member for engaging said nipple, a housing secured to said coupling member, an exhaust fan and driving motor mounted in said housing, and a flexible tubular member connected to said housing and extensible to a point outside said coverlet, whereby to produce a relatively low pressure area under the coverlet maintaining a flow of air inwardly through the coverlet and preventing the escape of malodorous air outwardly of the coverlet.

3. A portable and detachable odor adsorption device for removing offensive odors underneath the coverlet of a sick bed, litter or the like, said device comprising a canister disposable under said coverlet and having an outer casing and an inner casing defining a central air passageway, said casings having perforate side walls spaced from one another and closed at both ends, odor adsorption material filling the space between said walls, said air passageway being closed at one end and open at the opposite end, a flexible tubular member connected to the open end of

70 said passageway, means in said tubular member

for drawing purified air through said air passageway and discharging it through said tubular member to a point outside said coverlet, and projecting guard means secured to the outer casing of said canister for preventing direct contact between said outer casing and said coverlet and permitting access of air to said canister, whereby to produce a relatively low pressure area under the coverlet maintaining a flow of air inwardly through the coverlet and preventing the escape of malodorous air outwardly of the coverlet.

4. A portable and detachable odor adsorption device for removing offensive odors underneath the coverlet of a sick bed, litter or the like, said device comprising a canister disposable under said coverlet and having an outer casing and an inner casing defining a central air passageway, said casings having perforate side walls spaced from one another and closed at both ends, odor adsorption material filling the space between said walls, said air passageway being closed at one end and open at the opposite end, a nipple for said open end, a coupling member for engaging said nipple, a housing secured to said coupling member, an exhaust fan and driving motor mounted in said housing, a flexible tubular member connected to said housing and extensible to

5 a point outside said coverlet, and projecting guard means secured to the outer casing of said canister for preventing direct contact between said outer casing and said coverlet and permitting access of air to said canister, whereby to produce a relatively low pressure area under the coverlet maintaining a flow of air inwardly through the coverlet and preventing the escape of malodorous air outwardly of the coverlet.
